UNITED STATES PATENT OFFICE.

HOWARD L. PYLE, OF WILMINGTON, DELAWARE.

ACETYLENE-GAS GENERATOR.

SPECIFICATION forming part of Letters Patent No. 729,510, dated May 26, 1903.

Application filed June 3, 1902. Serial No. 110,116. (No model.)

To all whom it may concern:

Be it known that I, HOWARD L. PYLE, a citizen of the United States of America, residing at Wilmington, in the county of Newcastle 5 and State of Delaware, have invented new and useful Improvements in Acetylene-Gas Generators, of which the following is a specification.

This invention relates to acetylene-gas generators, and the object thereof is to provide in this class of machines a construction whereby the pressure within the apparatus (through the action of which the supply of carbid is regulated) may be confined within 10 as narrow a range between maximum and minimum pressures as possible, to the end that a more uniform operation of the carbid-feeding devices may be attained and incidentally to which construction the gas-holding chamber in the generator may also be kept within a much-narrower range of pressures than has heretofore been possible to my knowledge; and, broadly, the invention consists in providing a generating-chamber 15 of relatively small area which alone receives the pressure of the initial generation of gas when a charge of carbid is delivered, this generating-chamber being provided with outlets the area of which increases from the upper part of said chamber toward the lower, whereby increasing gas-pressure will, by the forcing downward of the column of water in said generating-chamber, uncover gas-outlets having proportionately larger areas than 20 those available for the escape of gas under a lower pressure.

Figure 1 of the drawings is an elevation, partly in section, of an acetylene-gas-generating apparatus applied thereto. Fig. 2 is a 25 vertical section, on an enlarged scale, of the lower end of the carbid-holder, a diaphragm and its actuating-spring, and means of connection between the diaphragm and the valve movable across the neck of the carbid-holder.

While the drawings in this case show the application of my invention to a specific type of apparatus, it is equally applicable to other types.

Referring now to the drawings, *a* indicates 30 the water-reservoir of a gas-generating apparatus of the class referred to, the upper portion of which reservoir, above the water-

level therein, constitutes the gas-holding chamber, which is indicated by *b*, and from which chamber, through an outlet-pipe *c*, gas 55 is taken to the burner. Relief-chambers *d* in the form of two stand-pipes enter the reservoir *a* through the top thereof, the ends of these relief-chambers being open and extending more or less below the normal level 60 of the water in said reservoir *a*. Ordinarily the upper ends of these relief-chambers are connected together by a pipe *e*, which is an escape-pipe having a branch leading to the atmosphere. These relief-chambers *d* are, 65 as is well known, for the reception of the water in the reservoir *a*, which may be forced into said chambers by gas-pressure, the height of the chambers determining the maximum pressure which may be accumulated in the 70 apparatus.

f indicates the usual carbid-holder communicating with the reservoir *a*, as usual, and between the carbid-holder and said reservoir there is a valve-casing *g*, having a valve therein for controlling the feed of the carbid, which valve is operated by a diaphragm *h*, which closes it and is opened by a suitable spring *h'*, Fig. 2, when the gas-pressure is reduced to such a point as to permit the spring to operate. When the spring *h'* moves the diaphragm to open the valve *h*, the latter is operated by means of an arm *h*², pivotally supported within the casing and connected by one end to said valve and by its opposite end 80 with the centrally-located stem *h*⁴ of the diaphragm. These parts are indicated in the drawings merely to illustrate a complete apparatus and are shown only as types, the invention not being necessarily associated with 85 this particular type of generator or of valve-operating mechanism.

The tubular connection *i*, which extends from the carbid-holder *f* to the reservoir *a*, is continued through the top of the latter 95 and is therein enlarged to form the initial-generating-chamber *j*, whose lower end is open and which extends downward to a point somewhat below the lower ends of the relief-chambers *d*. The casing of the diaphragm *h* is in 100 direct communication with said generating-chamber *j* through a suitable passage in the valve-casing *g*, as shown in Fig. 2, whereby the diaphragm is subjected only to the action

of the pressure within the initial generating-chamber *j*. In the walls of this chamber there are gas-outlets *k*, which are located above the normal water-line in the reservoir *a*, and 5 through these outlets *k* the generating-chamber *j* and the gas-holding chamber *b* are therefore normally in communication one with the other. Below the outlets *k* are other gas-outlets, *m*, located in the same horizontal plane, 10 whose united areas exceed the total areas of the gas-outlets *k*.

In the drawings the level of the water within the generating-chamber *j* indicates the position it would occupy when said chamber is 15 carrying substantially its maximum pressure under which the gas will escape not only through the outlets *k*, but also through the outlets *m*, whereby said pressure will be quickly reduced, the gas issuing from the outlets *m* passing up through the water into the gas-holding chamber *b*. During the operation of the apparatus, therefore, there would be present three levels of water, viz: that found in the relief-chambers *d*, that found 20 in the reservoir *a*, and that found within the initial generating-chamber *j*. The levels in the reservoir *a* and in the generating-chamber *j* show relative changes of position for a brief period only—that is, during such time 25 as is required for the pressure in *j* to become equalized with the pressure in the gas-holding chamber *b*.

The level of water within the relief-chambers *d* is governed entirely by the average 30 pressure in the upper part *b* of the reservoir *a* and in the generating-chamber *j*.

It is a well-known fact that in all acetylene-gas generators there takes place at the opening and closing movements of the carbid-40 feeding devices a slight feeding of carbid, owing to the slow action of the devices in opening or in cutting off this feed, operated, as they must be, by pressure which is relatively slow in accumulating. This more or 45 less prolonged dropping of carbid into the generating-chamber *j* would, if the outlets *k* were not present, eventually accumulate a pressure of gas which would drive the column of water within said chamber *j* low enough 50 to uncover the outlets *m*, when the confined gas would escape with a rush, thus subjecting the apparatus to more or less violent fluctuations of pressure within the gas-holding chamber; but these outlets *k* always being 55 in communication with said chamber *b* these accumulations within the chamber *j* become impossible, and these outlets *k* are so proportioned that even when the maximum charge of carbid is dropped they afford such 60 means of escape that an abnormal pressure in said chamber cannot occur. It is obvious, therefore, that with these outlets *k* on the one hand and the relatively small volume of water contained within the chamber 65 *j* on the other hand a quickly-generated volume of gas finds itself confined, as it were, in a space one of whose walls is quickly and

easily expansible, and there can be, therefore, no resulting back pressure on the diaphragm which would give the valve-closing devices a 70 quick or jolting movement, these devices only being operated to the fullest extent when the pressure of gas within the chamber *b* and the chamber *j* has been substantially equalized. Thus the relatively small column of 75 water within the chamber *j* acts as a sort of easily-yielding cushion to protect, on the one hand, the devices for controlling the feed of carbid from violent or irregular action and, on the other hand, maintaining the pressure 80 within the gas-holding chamber *b* at a point which varies but very slightly from the normal either way, and the result of the construction, as demonstrated by long practice in actual use, is great steadiness of the lights 85 supplied from this apparatus and the quiet, positive, and regular action of the devices controlling the carbid feed.

It is to be noted that in indicating the gas-outlets *k* and *m* in the drawings the attempt 90 has not been made to show the relative areas thereof, or the relative position thereof, or the relative number thereof, as these various characteristics may be varied to adapt the apparatus to varying conditions of work. 95

In the pipe *c* there is a three-way valve *c'*, and communicating with this valve and with the escape-pipe *e* is a pipe *c*², the pipe *c* being shown broken off above this valve *c'*. This three-way valve is so arranged, as usual in 100 machines of this type, that when the valve is turned in one direction a straight passage through the pipe *c* to the burner is provided, and when it is turned in another direction or in a greater degree in the same direction 105 the lower end of the pipe *c*, communicating with the gas-reservoir *b*, is placed in communication with the vent-pipe *c*² and communication between the pipe *c* and the burner cut off. 110

Having thus described my invention, what I claim, and desire to secure by Letters Patent of the United States, is—

1. In acetylene-gas-generating apparatus, a water-reservoir having a gas-holding space 115 therein, a generating-chamber of relatively small transverse area supported in said reservoir in contact with the water, there being in said generating-chamber gas-outlets located in different planes certain of which are 120 normally in communication with said gas-holding space, and certain of which are normally sealed by the water in the reservoir, in combination with a carbid-holder and a valve therefor, and means operated by the 125 pressure in said generating-chamber for moving said valve.

2. In an acetylene-gas-generating apparatus, a water-reservoir having a gas-holding space therein, a generating-chamber of relatively small transverse area supported in said reservoir, there being gas-openings in the wall 130 of said generating-chambers normally communicating with said gas-holding space, and

there being other openings through the wall of said chamber normally sealed by the water in said reservoir, a relief-chamber for said reservoir, and means for feeding carbide into said generating-chamber, in combination with a carbide-holder and a valve therefor, and means operated by the pressure in said generating-chamber for moving said valve.

3. In an acetylene-gas-generating apparatus, a water-reservoir having a gas-holding space therein, a generating-chamber of relatively small transverse area supported in said reservoir in contact with the water, a carbide-holder, a valve therefor and a diaphragm, operated solely by the pressure in the generat-

ing-chamber, to move said valve in one direction, said generating-chamber having gas-openings in the walls thereof of different areas, and located in different planes, certain of said openings communicating normally with said gas-holding space, and certain other of said openings being normally sealed by the water, whereby pressure in said chamber by displacing the water, may uncover said sealed openings. 20
